BOX

Bill James, Miami, Okla.

Application January 6, 1938, Serial No. 183,719

3 Claims. (Cl. 229—45)

My invention relates to improvements in boxes and closures therefor.

The invention is designed with the particular purpose in view of providing a practical inexpensive gift box having a prewrapped and tied body portion adapted to be filled, and closed, and sealed without disturbing the wrapper and ties thereof.

The above and additional objects, which will 10 hereinafter be more specifically treated, may be accomplished by means of the devices illustrated, in the accompanying drawings and set forth in the following specification, in the claims of which I have assembled and defined combinations of 15 parts and features of construction for which protection is desired.

In said drawings:—

Figure 1 is a view in perspective of a box constructed in accordance with my invention,

20 Figure 2 is a view in perspective of the closure member looking at the bottom thereof,

Figure 3 is a view in transverse vertical section,

Fig. 4 is a view in horizontal section taken on the line 4—4 of Figure 3 looking downwardly,

25 Figure 5 is a fragmentary view in transverse section showing the box inverted and illustrating the manner in which the closure member is applied.

30 Describing my invention in detail, with reference to the drawings by numerals, the box thereof comprises a preferably, although not necessarily, rectangular, open bottom body structure 1 of cardboard, or other suitable material, 35 having a top wall 2 and four side walls 3 turned at their bottom edges to form an internal lateral flange 4 extending around the lower edges of said body structure. A wrapper 5 of any desired character and ornamental design is provided over the 40 body structure 1 and cemented, or otherwise secured, thereto preferably to the underside of the flange 4. The wrapper 5 is further secured in position by means of cross ties 6, for instance of tape, extending over the top wall 2 and down 45 along the side walls 3 with ends thereof cemented, or otherwise secured, preferably to the underside of said flange 4. The ties 5 are secured together in the center of the top wall 2 by a cluster bow knot 6.

50 The described body structure 1 is designed to be filled from the bottom and packed by a tissue paper filler, as at 7, and a rectangular packing flap 8 of cardboard of the proper width in one direction to fit between two opposed edges of the flange 4 and sufficiently wide in the other direc-

tion to fit snugly between opposed side walls 3 in overlapping relation to the flange 4. As will be understood the packing flap 8 is inserted in the bottom of the box, in the position indicated, by flexing the same, and then slid along the flange 4 to one side of the box against one side wall 3.

The body structure 1 is closed by means of a closure member 9 in the form of a false bottom comprising a locking flap 10, a closure flap 11 and a sealing flap 12 constructed and related as follows:

The locking flap 10 comprises a rectangular piece of cardboard, or other similarly flexible material, of a width in one direction to fit between opposed side walls 3 and slide therebetween in 15 overlying position to the flange 4 and of a width in the other direction to be inserted between opposed edges of the flange 4. The locking flap 10 is designed to be inserted into the bottom of the body structure 1 in the same manner as flap 8 by 20 flexing, as shown in Figure 5, and then slid along the flange in the opposite direction to that in which flap 8 is slid and against the opposite side wall 3 of the box as shown in Figure 4, into what may be termed its locking position.

25 The closure flap 11 comprises a square of material which may be rigid, if desired, but is preferably cardboard and dimensioned to fit between the edges of the flange 4 and close the opening defined by said edges. The closure flap 11 is pivotally attached, as at 13, to one corner of the locking flap 10 in offset relation to the latter such that when said locking flap 10 is slid into locking, or normal, position the closure flap 11 will fit between the edges of the flange 4 and close the 30 opening defined thereby. The pivotal connection 13 of the closure flap 11 to the locking flap 10 provides for swinging the closure flap on the locking flap into registration with the edges of the flange 4 and for swinging said flap 11 to one side 35 when locating and removing the locking flap 10. In the described position of the closure flap 11, the locking flap 10 is secured in locking or normal position by coaction of the edges of the locking flap with the edges of the flange 4 and against 40 sliding movement into a position in which it may bulge through the opening and fall out of the structure 1 under the weight of the contents in the latter. On the other hand the locking flap 10 locks the closure flap 11 in closing position 45 as will be obvious.

45 The sealing flap 12 comprises a rectangular sheet of tissue, or other wrapping, paper preferably matching the wrapper 5 and cemented, or otherwise secured, to the bottom of the closure 50

flap 11. The sealing flap 12 extends beyond the edges of the closure flap 11 to provide sealing edges 14 adapted to underlie the flange 4. The sealing edges 14 are designed to be cemented, or pasted, to the underside of said flanges and for this purpose are preferably coated with an adhesive as indicated at 15.

When it is desired to open the described box the seal is broken by tearing the edges 14, the closure flap lifted on its pivot 13 out of the opening and swung to one side for use as a handle in sliding the locking flap 10 into a position such that it may be bent out of the opening and pulled therethrough. As will be manifest the box may, if desired, be opened from the side thereof opposite the described closure flap. Also the box may be made in various shapes.

The foregoing will, it is believed, suffice to impart a clear understanding of the structure, operation, and advantages of my invention.

Manifestly the invention, as described, is susceptible of modification both as regards structural details and combination of parts and right is herein reserved to all such modifications falling within the scope of the protection prayed.

What I claim is:—

1. In a box, an open bottom body structure including a top and side walls, respectively, said walls being inturned at their bottom edges to provide an internal lateral flange defining the opening in the bottom of the structure, and a closure assembly comprising a locking flap of semi-rigid material flexible for insertion into said opening in overlying relation to said flange and slidable on said flange to one side of the box into locking position, and a closure flap for the opening adapted to fit therein in edge to edge relation to said flange and connected to the locking flap in offset position thereon for swinging move-

ment thereon to one side thereof in the locking position of said locking flap.

2. In a box, an open bottom body structure including a top and side walls, respectively, said walls being inturned at their bottom edges to provide an internal lateral flange defining the opening in the bottom of the structure, and a closure assembly comprising a locking flap of semi-rigid material flexible for insertion into said opening in overlying relation to said flange and slidable on said flange to one side of the box into locking position, and a closure flap for the opening adapted to fit therein in edge to edge relation to said flange and connected to the locking flap in offset position thereon for such relation in the locking position of said locking flap, the connection between said flaps comprising a pivot providing for edgewise swinging movement of the closure flap on the locking flap to facilitate fitting the closure flap in said opening.

3. In a box, an open bottom body structure including a top and side walls, respectively, said walls being inturned at their bottom edges to provide an internal lateral flange defining the opening in the bottom of the structure, and a closure assembly comprising a locking flap of semi-rigid material flexible for insertion into said opening in overlying relation to said flange and slidable on said flange to one side of the box into locking position, and a closure flap for the opening adapted to fit therein in edge to edge relation to said flange and connected to the locking flap in offset position thereon for such relation in the locking position of said locking flap, and a sealing flap of flexible material overlying the bottom of the closure flap and the bottom of said flange and having portions coated with adhesive for attachment to said flange.

BILL JAMES.
